Gifford & Bull

UNITED STATES PATENT OFFICE.

MERCER G. FARRAR, OF CRANFORD, NEW JERSEY, ASSIGNOR TO THE CLOTHIEL COMPANY, OF NEW YORK, N. Y., A CORPORATION OF MAINE.

APPARATUS FOR LIQUIDS SEPARATING.

1,371,613.

Specification of Letters Patent. Patented Mar. 15, 1921.

Application filed March 6, 1920. Serial No. 363,778.

To all whom it may concern:

Be it known that I, MERCER G. FARRAR, a citizen of the United States, residing at Cranford, in the State of New Jersey, have 5 invented certain new and useful Improvements in Apparatus for Liquids Separating, of which the following is a specification.

My present invention relates to apparatus by which two liquids of different specific 10 gravities, which have become mixed or emulsified, may be separated.

One of the objects of my invention is to provide a simple apparatus by which two liquids, which have been shaken together to 15 form an emulsion, may be separated, and particularly an apparatus in which such separation may be carried on continuously and without a remixing of the liquids.

With these and other objects in view, my 20 invention consists in the apparatus herein-after described and more specifically pointed out in the appended claims.

In the drawings, Figure 1 is a longitudinal vertical elevation of one form of my 25 apparatus designed particularly to separate the lubricant from the refrigerant in refrigerating apparatus, the section being taken on the line 1, 1 of Fig. 2; Fig. 2 is a vertical sectional elevation on the line 2, 2 of Fig. 1; Fig. 3 is a vertical sectional elevation, and Fig. 4 is a plan view of a modification of my novel apparatus.

In the drawings the same parts in the different views are indicated by like reference 35 characters.

I have for purposes of illustration shown my novel apparatus in the form in which it can be readily applied to refrigerating machinery in which a refrigerant, such as ethyl 40 chlorid, coming from a compressor is shaken up and mixed with a lubricant, such as glycerin, which lubricant is heavier than the refrigerant.

In the illustrative arrangement shown in 45 Figs. 1 and 2, 10 is a horizontal tube, pipe or vessel in the right hand end of which through the pipe 13 the mixture of the two liquids is permitted to flow from any tank or reservoir 9. When used in connection 50 with refrigerating apparatus, this tank will be the condenser or cooler. At the left hand end of the pipe 10, there is a vertical standpipe 11, having its upper end expanded into a reservoir with a horizontal projection 12. On a portion of the pipe 10 and

preferably below the standpipe 11, is an outlet pipe 14. On the outer end of the projection 12 I provide a screw plug 15 in which is formed an outlet 16 controlled by a ball valve 17 having a float 18, and being 60 pivoted at 19. The float 18 is arranged so that when the liquid in the standpipe 11 rises to a predetermined height, the valve 17 will be opened to permit the liquid to pass out of the outlet 16. 65

In operation, the mixed liquids flow from tank 9, or some other source of supply, through the pipe 13, into the longitudinal pipe 10 which is made of sufficient length so that, as the liquids flow slowly toward 70 the outlet end of the pipe, the two liquids will separate into layers or strata with the heavier liquid at the bottom. Preferably, the parts are proportioned in relation to the rate of flow of the mixed liquids, so that 75 the plane of separation between the two will be below the center line of the pipe 10. When the liquids are thus separated, I have found that an attempt to draw off one from the other may so disturb the plane of separation that some of the other liquid will be carried away with the liquid that is being drawn off. I have found, however, that this difficulty will be overcome if at least the outlet for the liquid which preponderates 80 in the mixture be located at a considerable distance from the plane of separation of the liquids in the horizontal pipe. The disturbance produced by the eddies which are necessarily formed as the liquids flow out 85 of an orifice and which are developed proportionally to the rate and quantity of flow, is not permitted to reach the plane of separation, therefore, so that there is no remixing of the liquids as they are drawn off. 90 To accomplish this, I preferably place the outlet opening 16 not only at a considerable distance above the plane of separation between the two liquids in the pipe 10, but also preferably, as in the arrangement 95 shown in Figs. 1 and 2, considerably to one side of the vertical column of the lighter liquid. In such an arrangement, any currents which may be set up in the body of the lighter liquid in the projection 12 will 100 have no disturbing effect on the plane of separation between the two liquids in the pipe 10.

Therefore, when the lighter liquid has 105 filled the standpipe 11 and the extension 12 110

to a point where the ball 18 will be lifted to open the valve 17, the lighter liquid, which, in the apparatus illustrated, is a refrigerant, may flow through the outlet 16. When my 5 separating apparatus is used in connection with a refrigerating apparatus, the outlet 16 will connect directly with the expansion tank, and since the refrigerant is circulating continuously through the refrigerating 10 apparatus, the valve 17 will not be opened until sufficient of the refrigerant has been returned through the pipe 13 and the separating apparatus to raise the ball 18.

Preferably, and particularly when the 15 liquid passing through the outlet 16 is a refrigerant, such as ethyl chlorid, I arrange the levels so that the outlet 16 is always considerably submerged. In refrigerating apparatus, there is considerable difference in 20 pressure on opposite sides of the outlet, and I have found that, unless this outlet is kept submerged, the passing of the liquid from one pressure to the other tends to churn up the liquid in the standpipe, which in turn 25 disturbs the level of separation between the two liquids. By providing the float controlled valve, I insure a submergence of the outlet before any liquid can pass through it.

Moreover, when used with a refrigerant, 30 considerable variation in the level of the liquid in the standpipe will occur unless provision is made to control it. Thus, increase in the heat of the room, may increase the pressure in the space over the liquid and 35 thus lower the level. In order to obviate this, I preferably connect the space above the liquid in standpipe 11 with the space above the liquid in the tank 9, as by pipe 8. Hence any increase or decrease of pressure 40 above the liquid will not affect the level of the liquid.

In the form of apparatus shown in Figs. 3 and 4, there is a horizontal pipe or tube 20 having a vertical standpipe 21 at the right 45 hand end and a mixed fluid inlet 23 at the left hand end, and a heavy fluid outlet 24 at the bottom of the tube 20. Leading from the upper part of the standpipe 21 is an outlet 26 which, in this instance, is formed as a 50 pipe extending down through the standpipe and out through the end of the tube 20.

It will be seen that the arrangement shown in Figs. 3 and 4 is in many respects like that shown in Figs. 1 and 2, since the mixed 55 liquids enter at one end of a long horizontal tube in which the two liquids gradually separate, so that when the opposite end of the tube is reached, the lighter liquid may rise in the standpipe, from the upper end of 60 which it is drawn off, the outlet being at a considerable distance from the plane of separation between the two liquids in the pipe 20, such plane being, for instance, at the line indicated by a dot and dash line in Fig. 3.

The apparatus illustrated in the drawings 65 is particularly designed for the continuous separation of two liquids of which the lighter constitutes the larger part of the mixture. Consequently, the velocity of flow through the lighter liquid outlet will be 70 greater than that through the heavy liquid outlet. For this reason, I find it desirable to locate the light liquid outlet at a much greater distance from the plane of separation of the liquids than it is necessary to locate the heavy liquid outlet. 75

If the ratio of light and heavy liquids were reversed, so that the quantity of heavy liquid to be removed would greatly exceed the quantity of light liquid, then the arrangement of the parts preferably would be reversed so as to extend the vertical column downward to locate the heavy liquid outlet farther from the plane of separation than the light liquid outlet. By the use of the 80 vertical column, I am enabled to locate an outlet at a considerable distance from the plane of separation without greatly increasing the quantity of liquid held in the separating device and by locating this column 85 at a point removed from the inlet end, to insure that such column will be filled with only one kind of liquid.

It will be understood that the cross sectional area of the horizontal pipe or vessel 95 is preferably considerably larger than the cross sectional area of the inlet pipe so that the mixed liquids will move through the horizontal pipe at a velocity relatively very slow compared with the velocity of flow 100 through the inlet. This will permit the two liquids to separate before reaching the outlet end even with a comparatively short travel. If the apparatus is not designed to give this relatively slow horizontal velocity, then it 105 will be necessary to lengthen the horizontal pipe very considerably.

It will also be understood that suitable means may be provided to control the flow of the heavy liquid from the heavy liquid 110 outlet. This may be done by providing a valve in the outlet pipe or by constricting such pipe on the outlet itself.

It will also be understood that, in the form shown in Figs. 1 and 2, the extension or projection 12 provides a large pool from the top of which the lighter liquid is withdrawn. This large pool removes still further the possibility of disturbing the plane of separation between the liquids, because, obviously, any eddies in such a pool will be absorbed before being transmitted to the vertical column of liquid. This advantage is further actuated when the outlet is placed considerably to one side of the vertical column, as in Figs. 1 and 2. In case the vertical column extended downward, such a pool 120 may be advantageously used at the bottom 125

of the column, and likewise it will be preferable to locate the outlet in an extension at one side of the column.

While I have described my novel apparatus in the form in which I prefer to apply it to refrigerating apparatus, it will be understood that it may be used in separating any two liquids of different specific gravities, and particularly that it may be used in refrigerating apparatus in which refrigerants and lubricants other than those which I have indicated, are used.

It will also be understood that the apparatus may be varied within wide limits and that, indeed, the method which I have described, may be carried out by any suitable apparatus set up to that end.

I claim:

1. In a liquids separating apparatus, a horizontal conduit having an inlet arranged to permit the mixed liquids to enter at one end of said conduit and flow slowly toward the other end, said conduit having a vertical extension at the end opposite said inlet and a pair of outlets at said end and at opposite sides of the plane of separation of the liquid in said conduit, one of said outlets being at the end of said extension away from said conduit.

2. In a liquids separating apparatus, a horizontal conduit having an inlet arranged to permit the mixed liquids to enter at one end of said conduit and flow slowly toward the other end, said conduit having a vertical extension at the end opposite said inlet, said extension having an enlargement at its end away from said conduit, and a pair of outlets on opposite sides of the plane of separation of the liquids in said conduit, one of said outlets being in said enlargement.

3. In a liquids separating apparatus, a horizontal pipe having an inlet opening at one end, a vertical extension of said pipe at the end opposite said inlet, said vertical extension having a horizontal extension at its end away from said conduit and said horizontal extension having a fluid outlet at its end removed from said vertical extension, said conduit having an outlet on the side of the plane of separation of the liquids in said conduit which is opposite said vertical extension.

4. In a liquids separating apparatus, a horizontal pipe having an inlet opening at one end, a vertical extension of said pipe at the end opposite said inlet, said vertical extension having a horizontal extension at its end away from said conduit and said horizontal extension having a fluid outlet at its end removed from said vertical extension, said conduit having an outlet on the side of the plane of separation of the liquids in said conduit which is opposite said vertical extension, and a valve controlled by

the level of the fluid in said horizontal extension to control said outlet in said extension.

5. In a liquids separating apparatus, a horizontal pipe having an inlet opening at one end and a heavy liquid outlet at its bottom at a point removed from said inlet end, an upward extending vertical column at the end of said pipe opposite to said inlet end, said vertical column being expanded at its upper part to provide space for a relatively large part of the lighter fluid and a light fluid outlet in the upper part of said vertical column.

6. In a liquids separating apparatus, a horizontal pipe having an inlet opening at one end and a heavy liquid outlet at its bottom at a point removed from said inlet end, an upward extending vertical column at the end of said pipe opposite to said inlet end, said vertical column being expanded at its upper part to provide space for a relatively large part of the lighter fluid, a light fluid outlet in the upper part of said vertical column, and a valve controlled by the level of the light fluid, to control said outlet.

7. In a liquids separating apparatus, a horizontal pipe having an inlet opening at one end and a heavy liquid outlet at its bottom at a point removed from said inlet end, an upward extending vertical column at the end of said pipe opposite to said inlet end, and a light fluid outlet in the upper part of said vertical column.

8. In a liquids separating apparatus, a horizontal pipe having an inlet opening at one end and a heavy liquid outlet at its bottom at a point removed from said inlet end, an upward extending vertical column at the end of said pipe opposite to said inlet end, and a light fluid outlet in the upper part of said vertical column, the cross sectional area of said pipe being considerably larger than the cross sectional areas of said inlet pipe.

9. In a liquids separating apparatus, a horizontal pipe having an inlet opening at one end and a heavy liquid outlet at its bottom at a point removed from said inlet end, an upward extending vertical column at the end of said pipe opposite to said inlet end, a liquid outlet in the upper part of said vertical column, a valve to control said outlet and means to prevent the opening of said outlet unless said outlet is submerged by the liquid in said column.

10. In a liquids separating apparatus, a horizontal pipe having an inlet opening at one end and a heavy liquid outlet at its bottom at a point removed from said inlet end, an upward extending vertical column at the end of said pipe opposite to said inlet end, a liquid outlet in the upper part of said vertical column, a valve to control said outlet and a float connected to said valve and arranged to open said valve only when the

level of the liquid in said column is at a predetermined height above said outlet.

11. In a liquids separating apparatus, a horizontal pipe, a supply tank, an inlet tube connecting said tank with one end of said pipe, a vertical extension of said pipe at the end opposite said inlet, a heavy liquid outlet in the bottom of said pipe, a light liquid outlet in the upper part of said column and 10 a connection between the space above the fluid in said column and the space above the fluid in said tank.

12. In a liquids separating apparatus, a horizontal pipe, a supply tank, an inlet tube

connecting said tank with one end of said pipe, a vertical extension of said pipe at the end opposite said inlet, a heavy liquid outlet in the bottom of said pipe, a light liquid outlet in the upper part of said column and a connection between the space 15 above the fluid in said column and the space above the fluid in said tank, and a float controlled valve for said outlet arranged to close said outlet when the level of the liquid in said column falls below a predetermined 20 point above said outlet.

MERCER G. FARRAR.
